CLAIM

The ornamental design for a UVC LED box, as shown and described.

DESCRIPTION

FIG. 1 is a perspective view of a UVC LED box, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view thereof, with the design shown in use;

FIG. 9 is another perspective view thereof showing the design in alternate state of use;

FIG. 10 is an enlarged view of the selected portion in FIG. 6; and,

FIG. 11 is an enlarged view of the selected portion in FIG. 9.

The dot-dot-dash lines in FIGS. 10 and 11 represent the bounds of the enlargements taken from FIGS. 6 and 9 and form no part of the claimed design. The remaining broken lines depict portions of the UVC LED box that form no part of the claimed design.

1 Claim, 8 Drawing Sheets
